DISPENSING CLOSURE FOR A BOTTLE OR THE LIKE

Woodrow S. Wilson, Pasadena, Calif., assignor to Polytop Corporation, Slattersville, R.I., a corporation of Massachusetts

Filed Dec. 6, 1965, Ser. No. 64

Term of patent 14 years

(Cl. D58—26)

FIG. 1

FIG. 2

FIG. 3

FIG. 4

FIG. 5

FIG. 1 is an isometric view of dispensing closure for a bottle embodying my new design, the dispensing spout being shown in closed position;

FIG. 2 is an isometric view thereof taken at right angles to the view of FIG. 1 showing the spout in dispensing position;

FIG. 3 is a top plan view thereof showing the spout in closed position;

FIG. 4 is a side elevational view thereof, the opposite side elevational view being identical;

FIG. 5 is a front elevational view thereof, the rear elevational view thereof being plain and having striations all the way around, similar to FIG. 4.

The characteristic feature of the design resides in the flat top surface surrounded by a short vertical wall concentric with a rounded convex corner shoulder disposed

therebeneath, both of which extend around the entire upper edge of the closure except for the spout receiving recess.

I claim:

The ornamental design for a dispensing closure for a bottle or the like, substantially as shown and described.
